UNITED STATES PATENT OFFICE.

CHRIS BORGREN, OF BURBANK, SOUTH DAKOTA.

GAS-LINE CUT-OFF.

Application filed March 27, 1923. Serial No. 627,969.

To all whom it may concern:

Be it known that I, CHRIS BORGREN, a citizen of the United States, residing at Burbank, in the county of Clay and State of 5 South Dakota, have invented certain new and useful Improvements in Gas-Line Cut-Offs, of which the following is a specification.

The primary object of my said invention 10 is the provision of a cut off for the gasoline line of motor vehicles that is comparatively simple of construction, and easy of application, the device adapted to be operated by the driver of the motor vehicle for quickly 15 cutting off the flow of gasoline to the carburetor, which will thereby effectively prevent the starting of the motor, which will greatly lessen the liability of the automobile being stolen.

20 A further object of my invention is a cut off for the gas line of a motor vehicle that is comparatively simple of construction, and inexpensive of manufacture, the same consisting of relatively few parts, and these so 25 correlated as to reduce the liability of derangement to a minimum.

The nature and advantages of the invention will be better understood when the following detailed description is read in connection with the accompanying drawings, 30 the invention residing in the construction, combination, and arrangement of parts as claimed.

In the drawings forming part of this application, like numerals of reference indicate similar parts in the several views, and wherein:

Figure 1 is a fragmentary longitudinal cross sectional view of a portion of a motor 40 vehicle equipped with my improved cut off.

Figure 2 is a vertical transverse cross sectional view thereof.

Figure 3 is a vertical longitudinal cross sectional view on the line 3—3 of Figure 1.

45 Figure 4 is a perspective of one of the elements of my invention.

Figure 5 is a fragmentary sectional view through the motor vehicle floor board for showing more clearly the operating means 50 of my improved cut off, this operating means being also shown in cross section.

Figure 6 is a detail view of the valve connection for controlling the vacuum tank.

Referring to the drawings in detail, 55 5 the vehicle dash, 6 the usual vacuum tank, 7 the gas line from the tank

to the carburetor, and 5' the vehicle floor board. These elements are all found in motor vehicles of conventional types, and do not constitute the essence of my invention, 60 the same being shown for more adequately disclosing my improved cut off.

The said gas line 7 is equipped with a desirable form of valve 8, the same being preferably adjacent the end of the line 7 that 65 connects with the vacuum tank 6. This valve 8 is formed with an operating arm or lever 9, to which is connected as at 10, one end of a flexible cable 11.

Secured to the said dash board 5 and at a 70 point preferably upon the side opposite thereof from the said exhaust tank is a supporting bracket designated in general by the numeral 12. As more clearly shown in Figures 1 and 2, this bracket 12 comprises 75 a pair of spaced L-shaped arms 13, the same being interconnected by a pair of cross arms 14. Pivotedly secured to the arm 13 of the said bracket 12 remote from the vacuum tank 6, through the instrumentality of a 80 pivot pin 15 is a bell crank 16.

As shown in Figure 4, a strengthening bracket 17 is employed in conjunction with the pin 15, and connected to one arm of the said bell crank 16 is the opposite end of the 85 said flexible cable 11. Between this arm of the said bell crank and the dash 5 is a coiled spring 18, the same adapted for normally swinging the said bell crank upon its pivot for consequently maintaining the 90 said valve 8 in the gas line 7 closed.

Pivotedly secured as at 19 to one of the said cross arms 14 between the L-shaped arms 13 constituting the bracket 12 is a somewhat arcuate-shaped rod or arm 20, 95 the front end thereof being hooked as at 21. Between the opposite end of the said member 20 and an eye bolt 22 upon the dash 5 is a relatively strong coiled spring 23, the same adapted for normally maintaining the arm 100 or rod 20 in the position shown in several of the figures, and it will at once be apparent that when this arm or rod 20 is in the position shown, the other arm of said bell crank 16 is effectively maintained in such a 105 position as to overcome the tension of the spring 18 for consequently permitting the valve 8 of the gas line 7 to be opened.

Connected at one end as at 23' to the said arm or rod 20 is a flexible cable 24, the same 110 extending downwardly, and thence over a pulley 25 upon the said dash 5. This cable

24 is in turn engaged over a pulley 26 upon the said floor board 8 of the vehicle, and is connected at its opposite end as at 27, to one end of a control rod 28. The said rod 28 is 5 slidable within a cylinder 29, and is formed at one end with a head 30. Between an abutment 31 upon said rod 28, and the head thereof, is a coiled spring 31', the same adapted for normally maintaining the rod 10 up within the cylinder as more clearly shown in Figure 5. The cylinder 29 is formed upon a plate 32, it being of course understood that one end of this cylinder projects through an opening in said floor board, the 15 said plate 32 being anchored at 33 to the floor board.

In view of the above description, it will be seen that when the several parts are positioned in the several views, the said valve 8 20 of the gas line 7 may be opened. Whenever it is desired to close this valve, the said rod 28 is pressed downwardly by the operator's foot this downward movement of the rod causing a pull upon the cable 24 25 for consequently swinging the arm upon the pivot 19, the arm of the bell crank beneath the hooked end is released, the said spring 18 consequently swinging the bell crank upon its pivot 15, which movement will 30 effectively close the said valve 8.

Although I have herein shown and described the preferred embodiment of the

present invention, it is nevertheless to be understood that minor changes may be made therein, without departing from the spirit 35 and scope of the invention as claimed.

Having thus described my invention, what I claim as new, and desire to secure by Letters Patent is:—

1. In a cut out for gas lines of motor vehicles, wherein the same is provided with a cut off valve, a bracket secured to the vehicle dash board, a bell crank pivoted to said bracket, a connection between one arm of said bell crank, and the said valve of the gas line, 40 means for swinging said bell crank upon its pivot for closing said valve, and means for maintaining said valve crank in a position whereby said valve may be opened.

2. In a cut out for gas lines of motor vehicles, wherein the same is provided with a cut off valve, a bracket secured to the vehicle dash board, a bell crank pivoted to said bracket, a connection between one arm of said bell crank, and the said valve of the 45 gas line, means for swinging said bell crank upon its pivot for closing said valve, and means for maintaining said valve crank in a position whereby said valve may be opened, 50 and a foot pedal operatively connected to 55 said last mentioned means, whereby said bell crank may be released.

In testimony whereof I affix my signature.
CHRIS BORGEN.
